UNITED STATES PATENT OFFICE

1,931,792

NOZZLE

Giuseppe Giordano, West Nyack, N. Y.

Application July 16, 1932. Serial No. 622,990

1 Claim. (Cl. 299—114)

My invention relates to improvements in nozzles adapted for spraying more or less heavy liquids, such as asphalt, macadam, tar, 110 penetrating oil, or the like.

5 An important object of the invention is to provide a nozzle which will produce the advantages of the nozzle shown in Letters Patent No. 1,816,645, granted to me under date of July 28, 1931, but which is simpler and is formed of 10 fewer parts.

Other objects and advantages of the invention will be apparent during the course of the following description.

In the accompanying drawing, forming a part 15 of this specification, and in which like numerals are employed to designate corresponding parts throughout the same,

Figure 1 is a side elevation of the nozzle embodying my invention,

20 Figure 2 is a central vertical longitudinal section through the same,

Figure 3 is a front end elevation of the body portion of the nozzle, and,

25 Figure 4 is a section taken on line 4—4 of Figure 3.

In the drawing, wherein for the purpose of illustration is shown a preferred embodiment of my invention, the numeral 10 designates the body portion of the nozzle, and this body portion 30 is provided with an annular set of longitudinal ports or openings 11. These ports or openings are longitudinally inclined in a circumferential direction, preferably at an angle of about 16° from the longitudinal axis of the body portion. 35 As stated, the ports 11 are circumferentially inclined, but do not converge or diverge forwardly, and their longitudinal sides are, therefore, parallel with the side of the body portion. A recess or chamber 12 is formed in the rear end 40 of the body portion, and is in communication with the rear ends of the longitudinal ports 11. This recess extends radially beyond the ports 11. The body portion includes a tubular screw-threaded neck or extension 13, for connection 45 with a suitable hose, or the like, through which the heavy liquids are supplied under suitable pressure.

The numeral 14 designates a spreader element having a central opening 15, which leads at its 50 rear end into a rearwardly diverging recess 16. The wall of this recess 16 is, therefore, generally conical, inclined, and converges forwardly. Particular attention is called to the fact that the wall of the recess 16 extends radially beyond the forward ends of the ports 11, and also

radially inwardly beyond these ports. The arrangement is such that the heavy liquid discharging through the ports will strike the intermediate portion of the wall of the recess 16 at an angle, and rotary motion is imparted to the 60 oil so that it travels around this wall, and is conducted thereby inwardly so that it discharges, while whirling, through the contracted opening 15. The spreader element is provided with a forwardly flaring recess or opening 17, which is 65 generally conical and leads at its contracted end, into the contracted opening 15. The whirling or rotating heavy liquid passing through the opening 15 will again increase in diameter as it passes forwardly through a recess 17.

70 The spreader element 14 has its body portion externally threaded, as shown at 18, to have screw-threaded engagement within an internally threaded sleeve 19, which is screwed upon the threaded forward portion 20 of the body 75 portion 10. The sleeve 19 forms a chamber 21, between the body portion 10, and spreader element 14, and this sleeve also permits of the longitudinal adjustment of the spreader 14, with relation to the body portion 10. It is thus 80 seen that the spreader element is directly mounted upon the sleeve or wall of the recess 21, and a highly simplified and inexpensive construction is afforded. I am thus enabled to eliminate element 20 and associated elements 85 disclosed in my prior patent.

The operation of the nozzle is as follows:—

As before stated, the nozzle is particularly well adapted to be used in connection with heavy liquids, such as are applied to roads. 90 The nozzle may be suitably connected with a hose leading into a wheeled tank, traveling upon the road. The heavy liquid is fed to the nozzle, preferably at a low pressure of from 15 to 20 pounds to the square inch. The heavy 95 liquid first passes through the circumferentially inclined relatively long ports 11, and upon discharging from the forward end of these ports, it is introduced into the chamber 21, and a rotary whirling motion imparted thereto within 100 this chamber. The heavy liquid is rotating about the central longitudinal axis of the nozzle, and when the rotating mass engages the outer or intermediate portion of the wall of the recess 13, such rotating mass is radially contracted and guided through the contracted opening 15. Upon passing through the opening 15, the rotating mass radially expands upon entering the forwardly flaring conical recess 17. 110 Upon discharging from the recess 17, the rotat-

ing mass will have a relatively large diameter before reaching the road, and the rotating mass will be uniformly sprayed upon the road, over a large surface.

5 It is to be understood that the form of my invention herewith shown and described, is to be taken as the preferred example of the same, and that various changes in the shape, size and arrangement of parts may be resorted to, without departing from the spirit of my invention, or the scope of the subjoined claim.

Having thus described my invention, what I claim is:

10 A nozzle for spraying heavy liquids at low pressure, comprising a tubular body portion affording a long chamber, a rear end element secured to the tubular body portion and having an annular set of longitudinal ports which

are circumferentially inclined and lead into the rear end of the long chamber, means whereby a hose may be attached to the rear end element for supplying the heavy liquid to the ports, and a spreader element bodily mounted upon the forward end of the tubular body portion and engaging at its periphery with the tubular body portion to close the tubular body portion at such point of engagement, the spreader element being provided centrally thereof with a contracted opening and being provided upon its rear end with a shallow forwardly converging conical recess and upon its forward end with a deep conical recess flaring forwardly, the inner reduced ends of both recesses leading into the contracted opening, the forward recess being considerably longer than the rear recess.
